UNITED STATES PATENT OFFICE.

VICTOR GUINZBURG, OF NEW YORK, N. Y., ASSIGNOR TO THE I. B. KLEINERT RUBBER COMPANY, OF NEW YORK, N. Y., A CORPORATION OF WEST VIRGINIA.

HOSE-SUPPORTER.

SPECIFICATION forming part of Letters Patent No. 739,411, dated September 22, 1903.

Application filed June 20, 1902. Serial No. 112,412. (No model.)

To all whom it may concern:

Be it known that I, VICTOR GUINZBURG, a citizen of the United States, residing in the borough of Manhattan, city and State of New York, have invented certain new and useful Improvements in Hose-Supporters, of which the following is a specification.

My improvement relates particularly to hose-supporters having at the lower extremities of hose-supporting members clasps for engagement with the upper edges of the hose, and the improvement is in the clasp.

The object of this invention is to enable the clasp to obtain a firmer seat upon the button than usual, and thus more securely hold the material in place.

The invention consists of a hose-supporting clasp for carrying out the above objects, embodying the features of construction, combinations of elements, and arrangements of parts having the general mode of operation substantially as hereinafter fully described and claimed in this specification and shown in the accompanying drawings.

In the accompanying drawings, Figure 1 is a view of the lower end of a hose-supporting member embodying my improvement. Fig. 2 is a longitudinal section.

Similar letters of reference designate corresponding parts in both figures.

A designates the lower portion of a hose-supporting member, which may be made of tape, elastic or inelastic. At its extremities it is bifurcated or made to comprise two overlapping parts a' a^2 . The part a' has attached to its end a loop a^3 , preferably made of metallic wire and which is made to taper toward its free end. The other part, a^2 , has attached to its end portion a button-shaped projection a^4 , which, as here shown, extends from a base a^5 of metal, slotted to receive stitches whereby it may be secured in position. From the base extends a stud a^6 , and around this stud is fitted an eyelet a^7 . This eyelet is made of suitable rigid unyielding material which is capable of being easily worn away or permanently modified in form by the coaction of the loop a^3 with it in use. This eyelet, by reason of being made of such rigid unyielding material, can be made larger than is ab-

solutely necessary for operation with the loop and then worn or permanently deformed so as to be certain of having the proper coaction with the loop. It will preferably be of smooth surface material, such as celluloid, so that it will not have any abrading effect on the hose. 55

I am aware that it has been proposed to use rubber of the grade usually employed for lead-pencil erasers in buttons of this class, but with rubber of this kind the elasticity of the material is the important factor in the operation of the clasp. Such material, however, is not very durable. 60

I find that celluloid is the best material for use according to my invention, since it will easily become sufficiently worn or deformed by the action of the loop thereon to operate with facility, and when worn to final and desired shape such a button having a shank of celluloid or its equivalent for this purpose is 70 practically indestructible.

What I claim as my invention, and desire to secure by Letters Patent, is—

A hose-supporting clasp, comprising a metallic loop having a contracted portion tapering toward its free end, and a button having a metallic base with a stud extending therefrom, a covering upon the stud in the form of an eyelet composed of rigid, unyielding material and formed originally too large for the engagement of the contracted and tapering portion of the loop therewith, said loop thereby tightly gripping the eyelet so that the rigid and unyielding material of the eyelet which is capable of being easily worn away by coaction with the tightly-gripping metallic loop, becomes permanently modified in shape and hollowed until the proper bearing is afforded for the loop upon the eyelet, the surface of the eyelet being smooth to prevent an abrading effect on the material held between the eyelet and the loop, for substantially the purposes set forth. 85 90

In testimony whereof I have signed my name to this specification in the presence of two subscribing witnesses. 95

VICTOR GUINZBURG.
